UNITED STATES PATENT OFFICE.

WILLIAM A. WHITCOMB, OF MILLINOCKET, MAINE.

APPARATUS FOR STORING AND HANDLING LOGS.

1,380,280.

Specification of Letters Patent. Patented May 31, 1921.

Application filed October 24, 1919. Serial No. 332,898.

To all whom it may concern:

Be it known that I, WILLIAM A. WHITCOMB, a citizen of the United States, residing at Millinocket, in the county of Penobscot and State of Maine, have invented certain new and useful Apparatus for Storing and Handling Logs, of which the following is a specification.

This invention pertains to an improved apparatus for storing and handling logs, whereby they may be piled in bulk and thereafter removed when it is desired to use the same. More specifically, the invention relates to an apparatus whereby pulp wood, in log form, may be piled up for storage in summer and reclaimed therefrom in winter for use in making paper pulp.

The apparatus shown in the annexed drawings is capable of piling from 35,000 to 40,000 cords at a rate of substantially 750 cords per day (24 hour day), the construction being such that when the wood is piled it may be withdrawn from the bottom of the pile and transferred by the same conveyer which piled it to a transfer mechanism or other conveyer which leads to the mill.

Broadly stated, the invention may be said to comprise two main towers separated a considerable distance apart, (say 400 feet), a tunnel provided with removable covers extending between and beyond each of the towers, an inclined runway extending from a sluice or other log conveying means to the upper portion of one tower, and an endless conveyer which passes up the runway to a point adjacent the upper end of one tower, thence across to the other tower, downwardly therein and to a suitable driving means, thence through the tunnel and back to the point where the logs are fed to the runway.

In operation, the logs are automatically carried up the runway and are discharged from the endless conveyer and drop adjacent the tower which is next to the runway, the logs forming a cone shaped pile, which pile when it reaches a height equal to the elevation of the horizontal upper stretch of the cable, forms a support for the logs which are carried along the top of the pile and dropped so that the pile is gradually built up between the two towers. In order to facilitate the passage of the conveyer and the logs along the pile, I preferably

employ a sectional trough which will be extended along the top of the pile from time to time toward that tower which is remote from the runway. When the pile is completed between the two towers, which, in practice, have been spaced about 400 feet apart, and it becomes desirable to remove the logs, the traverse of the conveyer is as here shown reversed and as the covers are removed from the tunnel the logs drop therein and are fed outwardly from the bottom of the pile to a suitable conveying mechanism which transfers them to the mill or other point. Reversal of travel is not necessary if the mill and source of supply are at the same end of the tunnel or structure.

A preferred form of apparatus is shown in the accompanying drawings, wherein,—

Fig. 1 is a side elevation of the apparatus; 75

Fig. 2 an enlarged vertical sectional view showing the lower end of the runway, the sluice which is located in proximity thereto, and the conveyer cable with the sprocket wheel about which it passes at that point; 80

Fig. 3 a detail plan view of the means employed for applying the necessary tension to the cable;

Fig. 4 an enlarged vertical sectional view, broken away, of one of the intermediate 85 supporting towers or columns for the runway;

Fig. 5 a vertical sectional view taken on the line V—V of Fig. 4;

Fig. 6 a transverse vertical sectional view 90 taken on the line VI—VI of Fig. 4;

Fig. 7 a vertical sectional view, partly broken away, with the two main towers and the underlying tunnel;

Fig. 8 a vertical sectional view showing 95 the temporary support or guideway employed for the conveyer cable and the logs fed forward thereby upon the top of the pile of logs as the same builds up between the two main supporting towers; 100

Fig. 9 a perspective view of a section of such guideway;

Fig. 10 a detailed vertical sectional view on an enlarged scale showing a portion of the tunnel and the guideway for the cable; 105 and

Fig. 11 a transverse vertical sectional view taken on the line XI—XI of Fig. 10.

Referring to the drawings, 1 and 2 indicate the main towers which will be of substantial height and which, in practice, have been made 120 feet. Said towers are connected at their tops by a wire cable 3 and are back-stayed by similar cables 4 and 5. To the right of the tower 1 there is provided a series of columns or towers, denoted by 6, 7 and 8, the towers successively decreasing in height from the main column 1, as clearly indicated in Fig. 1. Said towers form the support for beams or girders 9, said beams being secured to the upper portion of the various towers 6, 7 and 8, and likewise at 15 their upper end secured to the tower 1.

At the lower end the beams find a bearing and support in a masonry foundation 10, best shown in Fig. 2. The beams 9 form the support for a runway 11, which is preferably V-shaped or concave in form (see Fig. 5) and provided with wear plates 12. A footway or platform 13 extends along the side of the runway (see Fig. 5) and a rail 14 is provided so that an attendant may 20 readily walk along the footway or platform when occasion requires. The foundation 10 also forms as here shown the support for one end of a sluiceway, denoted by 15, through 25 which the logs pass into line with the lower end of the runway. A series of rollers 16 are provided so as to facilitate the movement of the logs by an attendant and through the sluice into and between guide plates 17 located at the lower end of the 30 runway. The foundation 10 is provided with a pair of tracks 18 which preferably stand at the same inclination as the runway 11 and a truck 19 is mounted upon said tracks. The truck is held in its adjusted 35 position upon the track by means of threaded rods 20 which at their lower ends are anchored into a suitable foundation, the rods at their upper ends passing through the lower cross elements of the truck and have 40 threaded thereon nuts 21 which are interconnected by a sprocket chain 22 or other suitable mechanism so that they may be simultaneously adjusted to move the same upwardly or downwardly along the tracks 18. 45 Said truck forms the support or bearing for the sprocket wheel 23 about which passes a wire cable 24 provided with a series of buttons or locking members 25 adapted to engage the logs as they are dropped into the runway and move the same upwardly along 50 said way. The cable 24 as it leaves the upper end of the runway passes over a similar sprocket wheel 26 mounted in the tower 1, thence across to the tower 2 and over a 55 sprocket wheel 27 mounted in said tower 2, thence downwardly through said tower and about the sprocket wheel 28 located at the bottom of said tower, and thence laterally in the tunnel about a drive sprocket 29 and

thence in a reverse direction through the 65 tunnel back to the sprocket 23. By the arrangement above set forth in connection with the truck it may be adjusted so as to place the cable under proper tension.

The tunnel is denoted generally by 30 70 and would preferably be formed of suitable reinforced concrete or masonry. It extends from the tower 2 and beneath tower 1 and to a point in alignment with the tower or column 7. That portion of the tunnel which 75 lies between the towers 1 and 2 is substantially level and as it leaves the tower 1 may be given a slight upward inclination toward the tower 7. At the right of the tower 7 the floor of the tunnel is continued beneath the 80 tower 8 and to the foundation element 10, as denoted by 31. To the left of the tower 2 the tunnel extends to the sheave sprocket 29 and a conveyer trough 33 (Fig. 1) is provided at the end of such tunnel extension 85 and preferably adjacent the driving element 29 in order that the logs as they are removed from the tunnel may be transferred to the mill or any other desired point.

The upper face of the main portion of the 90 tunnel is preferably rabbeted or cut away adjacent each edge in order to form a bearing for the covering of the tunnel which will preferably be formed of logs 34 extending transversely of the tunnel, the logs 95 affording a covering which is at once strong and which may be readily positioned and removed as occasion requires.

As the log pile builds up and begins to 100 extend from the tower 1 toward the tower 2, it is found desirable to provide a temporary support or guideway for the cable and the logs which are moved forwardly thereby. Such construction is best shown in Figs. 8 and 9 wherein it will be seen that there is 105 provided a trough shaped member composed of cross supports or base pieces 35 having secured thereto three boards or timbers 36, 37 and 38, the two latter being arranged at an angle to the base board 36 so as to form a trough shaped structure. Metallic wear plates 39 are secured to said boards and extend outwardly beyond the boards at one end by stopping short at the opposite end. Such trough shaped elements 110 may be secured to each other from time to time and the guideway thus extended out over the pile as it grows toward tower 2.

It will be seen upon reference to Figs. 7 and 8 that there is provided at the upper 120 end of the tower 1 adjacent the sheave or sprocket 26, side plates 32 which form extensions of the runway and cause proper delivery of the logs. Said plates likewise coöperate with the extensible trough elements just referred to as the same are built outwardly over the top of the pile. A deflector plate 32a will likewise preferably be 125

provided for the logs adjacent the sheave 26 so as to deflect them slightly from the tower 1.

While ordinarily the logs will be removed 5 through the tunnel by a reversal of the travel of the cable or rope 24, means is provided whereby the upper stretch of the cable may be taken down and the cable caused to pass directly about the sprocket sheaves 23 10 and 29 without passing around the other sheaves at all. Inasmuch as only one run or stretch of the cable should be present in the tunnel proper, as a second run would interfere with the withdrawal of the logs 15 through the tunnel, there is provided at one side of the tunnel a pocket or way 40, best shown in Fig. 11. The pocket is closed by a series of gravitating doors 41, and as the pocket leaves the tunnel proper, or that 20 portion which is between the towers 2 and 7, it is continued in an upward direction, as shown in Figs. 1 and 6. By threading the cable through such pocket and allowing the other run to lie in the bottom of the 25 tunnel, it will be readily seen that the passage of the logs through the tunnel, by reason of engagement of the buttons 25 with the logs as they drop into the tunnel, will not be interfered with by the opposite run 30 of the cable.

From the foregoing it will be seen that the logs may be readily piled and left in bulk storage and be removed as occasion may require. Such removal may be effected 35 by reversing the drive of the cable, the cover logs 34 being removed adjacent the tower 2 so that the logs from the pile may drop into the tunnel. Such cover logs will be 40 successively moved as the pile shortens up between the towers until the entire pile has been transported log by log. Those logs 45 which will not run into the tunnel from the pile may be shoved or pushed thereinto by the workman and thus shifted to the transfer member 33.

What is claimed is:

1. In an apparatus of the character specified, the combination of a pair of spaced towers; an inclined runway extending upwardly toward the upper portion of one of said towers; a tunnel extending from one of said towers to the other; and conveyer means extending through the tunnel, up the runway, across from one tower to the other, 50 and back to the tunnel.

2. In an apparatus of the character specified, the combination of a pair of spaced towers; an inclined runway extending upwardly toward the upper portion of one of said towers; a tunnel extending from one of said towers to the other; a removable cover therefor; and conveyer means extending 55 through the tunnel, up the runway, across from one tower to the other, and back to the tunnel.

3. In an apparatus of the character specified, the combination of a pair of spaced towers; an inclined runway extending upwardly toward the upper portion of one of said towers; a tunnel extending from one of 70 said towers to the other; a sectional removable cover therefor; and conveyer means extending through the tunnel, up the runway, across from one tower to the other, and back to the tunnel.

4. In an apparatus of the character specified, the combination of a pair of spaced towers of a material height; an inclined runway extending downwardly and outwardly from one of said towers from a point near 80 its upper end; a tunnel extending beneath and intermediate said towers; an endless cable extending up the runway, spanning the space between the towers, thence passing downwardly to the tunnel, and through the 85 same to the lower end of the runway; means for driving the cable; and means carried by the cable for engaging logs.

5. In an apparatus of the character specified, the combination of a pair of spaced towers of a material height; an endless cable extending from one tower to the other from points adjacent their upper ends; means carried by the cable for engaging logs; means located to one side of one of said towers and coöperating with the cable to elevate logs; means for driving the cable; and an extensible guideway for the cable and logs adapted for placement on the piled logs 95 when the same reach the cable span extending between the towers.

6. In an apparatus of the character specified, the combination of a pair of high, spaced towers; a tunnel extending to each side of, beneath and intermediate the towers; 105 an inclined runway extending from an elevated point on one of said towers downwardly and to one side of the same; an endless driven cable passing about sprocket sheaves located at the lower and upper ends 110 of the runway, thence over a sprocket carried by the oppositely disposed tower, thence over a sprocket at the base of said tower, thence over and about a sprocket located at the end of the tunnel remote from the runway, and back through the tunnel to the first named sprocket; and means carried by the cable for engaging logs.

7. In an apparatus of the character specified, the combination of a pair of spaced 120 towers; an inclined runway extending downwardly and outwardly from one of said towers from a point near its upper end; a tunnel extending beneath and intermediate said towers; a pocket extending along one 125 side of the tunnel; means for laterally closing said pocket; an endless cable extending up the runway and spanning the space between the towers, thence passing downwardly to the tunnel, and through the same 130

to the lower end of the runway; means for driving the cable; and means carried by the cable for engaging logs, the pocket being provided for the purpose of taking care of one run of the cable when it is removed from the towers in the act of removing logs through the tunnel which have been previously piled thereon.

8. In an apparatus of the character specified, the combination of a pair of spaced towers of a material height; a foundation member located to one side of one of said towers; a plurality of towers of gradually increasing height located between said foundation member and the tower just mentioned; an inclined runway extending from said last mentioned tower to the foundation member and supported by the intermediate towers; a tunnel extending from a point beneath the runway and beneath the pair of spaced towers and to a point beyond the second of said towers; a sprocket sheave mounted on the foundation member; a sprocket wheel mounted adjacent the upper end of the first of said pair of towers; a similar sprocket mounted in the opposite spaced tower; a sprocket mounted at the lower end of said last named tower; a driving sprocket located at that end of the tunnel remote from the foundation member; a cable passing about said sprockets and through the tunnel whereby a span is formed

between the pair of spaced towers; and means carried by the cable for engaging logs.

9. In an apparatus of the character specified, the combination of a pair of spaced towers of a material height; a foundation member located to one side of one of said towers; a plurality of towers of gradually increasing height located between said foundation member and the tower just mentioned; an inclined runway extending from said last mentioned tower to the foundation member and supported by the intermediate towers; a tunnel extending from a point beneath the runway and beneath the pair of spaced towers and to a point beyond the second of said towers; a sprocket sheave mounted on the foundation member; a sprocket wheel mounted adjacent the upper end of the first of said pair of towers; a sprocket mounted at the lower end of said last named tower; a sprocket located at that end of the tunnel remote from the foundation member; a cable passing about said sprockets and through the tunnel whereby a span is formed between the pair of spaced towers; means carried by the cable for engaging logs; and means for presenting logs to the lower end of the runway.

In testimony whereof I have signed my name to this specification.

WILLIAM A. WHITCOMB.
